[57] CLAIM

The ornamental design for a video camera with video tape recorder, as shown and described.

DESCRIPTION

FIG. 1 is a front, top and right side perspective view of a video camera with video tape recorder showing our new design;

FIG. 2 is a rear, top and left side perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is a perspective view thereof with the viewfinder rotated 90° upwardly from the position shown in FIG. 1; and,

FIG. 10 is a perspective view thereof similar to that of FIG. 1 with the viewfinder tilted obliquely upwardly and rearwardly.

*FIG. 1**FIG. 2*FIG. 3

FIG. 4

FIG. 5

*FIG. 6**FIG. 7**FIG. 8*FIG. 9

FIG. 10
